UNITED STATES PATENT OFFICE

118,632

DESIGN FOR A DETACHABLE TOWEL RACK OR SIMILAR ARTICLE

Roy S. Sanford, Oakville, Conn., assignor to The
Autoyre Company, Incorporated, Oakville,
Conn., a corporation of Connecticut

Application November 6, 1939, Serial No. 88,063

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Detachable Towel Rack or Similar Article, of which the following is a specification, reference being had to the accompanying drawing forming a part thereof.

Fig. 1 is a perspective view of a detachable towel rack or similar article showing my new design;

Fig. 2 is a front elevational view of Fig. 1; and
Fig. 3 is a side elevational view of Fig. 1.

The dominant features of the detachable towel

rack or similar article are the provision of a pair of brackets each comprising spaced arms connected at one of the ends of each thereof and bars forming a closed loop secured to and between said brackets at the connection for the arms thereof, said closed loop lying in a plane at substantially a right angle to the longitudinal direction of the brackets and extending outwardly therefrom on each side thereof, all as shown.

I claim:

The ornamental design for a detachable towel rack or similar article, substantially as shown and described.

ROY S. SANFORD.
